SELF FEEDING RIP SAW MACHINE.

No. 452,110.

Patented May 12, 1891.

UNITED STATES PATENT OFFICE.

FRANK McDONOUGH, OF EAU CLAIRE, WISCONSIN.

SELF-FEEDING RIP-SAW MACHINE.

SPECIFICATION forming part of Letters Patent No. 452,110, dated May 12, 1891.

Application filed March 22, 1889. Serial No. 304,373. (No model.)

To all whom it may concern:

Be it known that I, FRANK McDONOUGH, a citizen of the United States, residing at the city of Eau Claire, in the county of Eau Claire 5 and State of Wisconsin, have invented a new and useful Improvement in Self-Feeding Rip-Saw Machines, of which the following is a full description, reference being had to the accompanying drawings.

10 This invention relates to machines for sawing or ripping boards or planks into strips of any desired width for various purposes; and it has for its object to construct a machine of this class which shall be simple and easily 15 operated, and in which the speed of the feed mechanism may be conveniently manipulated while the machine is in motion.

The invention consists in the improved 20 construction, arrangement, and combination 25 of parts, which will be hereinafter fully described, and particularly pointed out in the claim.

In the drawings hereto annexed, Figure 1 is an end elevation of a machine constructed 25 in accordance with my invention, parts of the same having been broken away for the purpose of showing the construction more clearly. Fig. 2 is a side elevation of the same. Fig. 3 is a detail view showing one end of a driving- 30 shaft and the sliding box in which the said shaft is mounted.

Like numerals of reference indicate like parts in all the figures of the drawings.

In the frame of my improved machine, 35 which is designated by 1, and which may be constructed of wood, iron, or other suitable material, is journaled a shaft or arbor 2, carrying the saw 3. Said shaft or arbor has a pulley 4, which is connected by a belt or band 40 5 with a drum 6 upon the driving-shaft 7. One end of the latter is journaled in a box 8, in which it has a limited sliding movement. The other end of said shaft is mounted in a box 9, which is slidably mounted upon a 45 flanged supporting-plate 10 in the frame of the machine. The portion of the shaft 7, which is journaled in the box 9, is slightly reduced in diameter, in order that the said shaft shall be moved with the box when the 50 latter is adjusted upon its supporting-plate. Motion will be transmitted to the shaft 7 in any well-known manner from some suitable

source of power, and the inner end of the said shaft carries a friction wheel or disk 11.

12 designates a shaft, which is mounted 55 vertically in a suitable step 13 and boxing 14 upon the frame 1. Mounted upon the said shaft near its lower end is a hub 15, carrying a friction-wheel 16, which may be constructed of or faced with wood, paper, or any other 60 suitable material. The hub 15 is mounted slidably upon the shaft 12, upon which it is keyed by means of a feather or spline working in a groove 17 in the said shaft. The hub 15 has a revolving ring 18, provided with laterally-extended studs 19, engaging slots 20, formed in a yoke 21 upon a lever 22, which is pivoted to the frame of the machine. Pivotally connected with the free end of the lever 22 is a rod 23, having screw-threaded portion 70 24 and provided at its upper end with a crank 25. Said screw-threaded rod extends through a nut 26, which is pivotally connected with the frame of the machine. The screw-threaded rod 24 is swiveled in the rod or arm 75 23, so that the said screw-threaded rod may be rotated in the nut 26, thus raising or lowering the free end of the lever 22, and thereby adjusting the friction-wheel 16 at a greater or less distance from the center of the disk 11, 80 and consequently regulating the speed at which the shaft 12 will be rotated.

Upon the upper end of the shaft 12 is mounted a vertically-sliding box 27, having a laterally-extending arm 28, the outer end of 85 which has a vertical screw-threaded perforation 29, through which extends an adjusting-screw 30, the upper end of which has a crank or handle 31 and the lower end of which bears against an arm or bracket 32, extending 90 from the frame of the machine. A spring, as 33, may be coiled upon the feed-screw below the arm 28, in order to assist in forcing the latter in an upward direction when desired. The sliding box 27 has a laterally-extending arm 34, in which is journaled a shaft 35, carrying a feed-saw or feed-wheel 36. The inner end of the shaft 35 has a bevel-gear 37 meshing with a pinion 38. The latter, as well as the bevel-gear 37, is located within the box 100 27, and the said pinion 38, which is vertically adjustable with the said box, is keyed upon the shaft 12, which latter is provided with a vertical groove 39 to accommodate the key

and to admit of the vertically sliding movement of the pinion.

It will be readily understood that by manipulating the screw 30 the boxing carrying the shaft upon which the feed-wheel is mounted may be adjusted vertically to accommodate lumber of any desired thickness, and that such adjustment may be effected while the machine is in operation, as well as the adjustment of the friction-wheel 16, whereby the speed of the shaft 12, and consequently the speed of the feed mechanism, may be regulated.

Suitably pivoted to the frame of the machine at 40 is a bent arm or lever 41. Said lever is preferably mounted upon a rock-shaft having an upwardly-extending arm or pawl 42 engaging the under side of the sliding box 9, in which one end of the driving-shaft 7 is journaled. Upon the horizontal arm of the lever 41 is mounted an adjustable weight 43, and the free end of said lever has a pivoted handle-bar 44 provided with teeth or notches 45, adapted to engage a yoke or stirrup 46, through which the said handle-bar extends. It will be seen that when the handle-bar 44 is not in engagement with said stirrup the weight 43 will tend to throw the shaft 7 in the direction of the shaft 12, thus holding the friction-disk 11 in contact with the wheel 16 with a degree of pressure which may be regu-

lated by adjusting the weight 43 upon the lever 41. By raising the free end of the lever 41 and suspending it by means of the notched handle-bar engaging the stirrup 46 the feed mechanism may be temporarily thrown out of operation.

From the foregoing description, taken in connection with the drawings hereto annexed, the operation and advantages of my invention will be readily understood.

The construction of my machine is very simple, and it may be easily manipulated in the manner herein described to regulate the speed of the feed mechanism.

Having thus described my invention, what I claim is—

In a machine of the class described, the combination of a vertical shaft, a friction-wheel mounted slidably upon the same, a shaft having a limited sliding movement and carrying a friction-disk adapted to engage the said friction-wheel, a rock-shaft, and a weighted lever mounted upon the latter and having a pawl engaging a sliding box in which one end of the driving-shaft is mounted, substantially as and for the purpose set forth.

F. McDONOUGH.
